UNITED STATES PATENT OFFICE.

CHARLES S. FORBES, OF BROOKLINE, MASSACHUSETTS, ASSIGNOR, BY DIRECT AND MESNE ASSIGNMENTS, TO UNION INDUSTRIAL COMPANY, OF KITTERY, MAINE, A CORPORATION OF MAINE.

SPINNING-RING.

1,333,072.

Specification of Letters Patent.

Patented Mar. 9, 1920.

Application filed October 12, 1916. Serial No. 125,280. Renewed April 17, 1919. Serial No. 290,904.

To all whom it may concern:

Be it known that I, CHARLES S. FORBES, a citizen of the United States, residing at Brookline, county of Norfolk, State of Massachusetts, have invented an Improvement in Spinning-Rings, of which the following description, in connection with the accompanying drawing, is a specification, like characters on the drawing representing like parts.

This invention relates to spinning rings of that type embodying an annular traveler which is confined between annular top and bottom members, examples of spinning rings of this type being shown in United States Letters Patent No. 857,535, dated June 18, 1907; No. 874,429, dated December 24, 1907, and No. 957,759, dated May 10, 1910.

The object of the present invention is to provide an improved spinning ring of this type which is constructed to reduce to a minimum the wear of the traveler upon the lubricating lining and the wear of the traveler on the yarn, and which is also constructed to provide a spinning ring capable of an increased speed of operation, and otherwise to improve spinning rings of this type, all as will be more fully hereinafter set forth.

30 In the drawings wherein I have illustrated a selected embodiment of my invention, Figure 1 shows a plan view of a spinning ring constructed in accordance with the invention;

35 Fig. 2 is a sectional view on the line 2—2, Fig. 1;

Fig. 3 is a plan view showing the inner member of the ring attached to the rail plate;

40 Fig. 4 is a bottom plan view, partially in section, of the anti-friction bearing member or lining;

Fig. 5 is a perspective view of the traveler;

Fig. 6 is an enlarged section on the line

45 6—6, Fig. 1;

Fig. 7 is an enlarged fragmentary view of a portion of the traveler.

Fig. 8 is a vertical sectional view through the guide eye 8.

50 The main elements of my improved spinning ring are the same as are found in prior spinning rings of this type, that is, the spinning ring comprises an inner member 1 having an upturned flange 2, an outer

member 3 which sets over the inner member 1 and embraces the flange 2, a bearing member 4 which fits within the outer member 3 and encircles the flange 2 of the inner member 1 and which has an inwardly-projecting flange 5 that overlies the upper edge of the flange 2 but is separated therefrom, and an annular traveler 6 which is received in the space between the flange 2 and the bearing member 4 and is provided with an upwardly-directed stem 7 having a yarn guide 8 at its upper end.

The inner and outer members 1 and 3 are detachably secured together so that they can be readily separated in usual manner, that is, the outer member 3 is provided with the extension 9 having a notch to fit the retaining lip 10 on the inner member 1, and said outer member is also provided with the upturned resilient retaining finger 11 that has frictional engagement with a corresponding finger 12 on the inner member 1.

The assembled inner and outer members 1 and 3 are detachably secured to a rail plate 13 which in turn is secured to a ring rail in usual manner. This rail plate is provided with a retaining lip 14 which engages a notch formed in the inner member 1 and is also provided with an upturned resilient locking finger 15 that co-operates with the finger 12 of the inner member 1 to hold the parts in position. The rail plate 13 is provided with two pairs of oppositely-disposed notched projections 16, 17, these projections being for the purpose of receiving screws for attaching the rail plate to the ring rail. The purpose of providing two pairs of projections is so as to permit the rail plate to be attached to the ring rail in either one of two positions, depending upon which pair of notched projections is used.

95 One of the features of my present invention relates to a construction of the bearing member 4 by which the wear thereof due to the rotation of the traveler is greatly reduced. In spinning rings of this type, this bearing member 4 is usually made of wood which has been treated with some lubricating material for the purpose of making it self-lubricating. In the use of the spinning ring, the traveler rotates very rapidly, and in order to eliminate as far as possible any wear on this bearing member due to the action of the traveler, I propose to provide

the surface thereof with which the traveler contacts with one or more wear-resisting inserts. These wear-resisting inserts will take the wear of the traveler and will prevent the wood from wearing away to any appreciable extent. These inserts may be provided for in various ways without departing from my invention. I have herein shown the inserts in the form of metallic pins 18 and 19. The pins 18 are arranged horizontally and are situated in the plane of the traveler 6 so that said pins will take the wear of the traveler. The pins 19 are arranged vertically and are so positioned that they come flush with the inner face 21 of the bearing member 4. These wear-resisting inserts will receive the wear of the traveler but will not interfere with the action of the bearing member in providing necessary lubrication. While I have shown both vertical and horizontal pins, yet it may not be necessary in all cases to use both sets of pins and the wear-resisting inserts may be either horizontally or vertically arranged without departing from the invention.

The traveler 6 is made of sheet metal and it is provided with one or more depending aprons 20. I have herein illustrated one such apron which is situated directly opposite the stem 7. The purpose of the apron 20 is to make a relatively wide bearing surface between the traveler and the bearing member thereby reducing the wear of the traveler on the bearing member. The advantage of placing the apron directly opposite the stem 7 and yarn guide 8 is that said apron acts as a counterbalance for the stem and yarn guide. I propose to make the apron of such a size that it will have the same weight as the stem 7 and yarn guide 8, and by this means, a perfectly balanced traveler is produced. If desired more than one apron may be used, and these other aprons may be placed at various positions about the traveler, but if added aprons are used, they will preferably be so placed that they will balance each other.

The yarn guide 8 is formed by bending the end of the stem into proper shape, and in doing this, the extremity 22 is carried up parallel to the stem above the center of the loop thus formed and which constitutes the yarn guide 8. The space 23 between the extremity 22 and the stem 7 forms a thread passage through which the yarn may be threaded, and by having the thread passage 23 lead into the guide eye 8 above the center thereof, there will be no danger that said yarn guide will be de-threaded when the yarn becomes slack upon stopping the spinning machine.

It is desirable that the traveler should be as light as possible consistent with its having the requisite strength, and to this end I propose to make the traveler of very thin

material and to make the stem as narrow as possible. In order to strengthen the guide eye 8, I propose to make the portion of the stem from which said guide eye is formed with a transverse curvature and in order to produce a yarn guide which will present a smooth surface for the yarn, I will make this curvature such that the inner face 44 of the eye 8 is convex in a direction transversely to the stem. This manner of forming the yarn guide 8 not only makes a smooth thread-engaging surface, but also adds to the strength.

The extremity 22 of the stem is made rounding, as shown in Fig. 8, so as to facilitate the de-threading of the eye if occasion for this should arise. The stem 7 is connected to the traveler by an offset portion 45 so that the stem is situated inside of the inner periphery of the traveler. The advantage of this construction is that it permits the traveler to set farther under the overhanging flange 5 of the wooden bearing member or, in other words, it permits this flange 5 of the wooden bearing member to be made wider than would be possible if the stem 7 extended directly up from the inner periphery of the ring. With this construction, the traveler will be more securely held in place and all danger that it will be pulled out from under the flange 5 is obviated.

I will also preferably make the traveler curved transversely, as seen in Fig. 7, thereby to give it additional strength. The outer edge of the traveler will also preferably be bent inwardly, as shown at 24, to form a stiffening bead which adds to the strength of the traveler. This bead also has the advantage that it produces a rounded edge which tends to lessen the wear of the traveler on the bearing member 4. By making a traveler with the stiffening bead 24 and of the shape shown, it is possible to use very thin material for the traveler and yet have it sufficiently stiff and rigid to meet all requirements.

It is important that the bearing member 4 should fit tightly up against the top flange 25 of the outer member 3 so that the portion 5 of said bearing member may be properly spaced from the outer edge of the flange 2 and of the inner member 1. In the manufacture of the bearing member 4, it is found that the vertical dimensions of said member vary somewhat, due to the fact that some woods will shrink more than others. In order to provide for maintaining the bearing member 4 in proper position regardless of any slight variation in its vertical dimension and also to provide for holding said bearing member firmly in place and to prevent its rotating, I propose to provide the inner member 1 with a plurality of retaining projections 27 which are situated to engage the under face of the bearing mem-

ber 4. These retaining projections 27 are made with sharp points so that when the outer member is snapped onto the inner member, these projections will be pressed 5 into the under face of the wooden bearing member 4 and will thus hold said bearing member in position. The pressure of these points 27 against the bearing member will also force said bearing member firmly 10 against the flange 25 of the outer member and thus hold said bearing member securely in position. This result will be attained even though the bearing member varies in vertical dimension somewhat because if the 15 bearing member is slightly thicker than is shown in the drawing, the points 27 will merely be pressed farther into the bearing member, while if said bearing member is of less thickness than shown in the drawings, 20 the said points will be pressed thereinto to a less degree.

Having fully described my invention, what I claim as new and desire to secure by Letters Patent is:

25 1. In a spinning ring, the combination with an inner member and an outer member, of a self-lubricating bearing member confined between said inner and outer members and an annular traveler situated between 30 the bearing member and the inner member, said bearing member being provided with wear-resisting inserts positioned to be engaged by the traveler during its rotation, whereby a durable and properly lubricated 35 bearing for the traveler is provided.

2. In a spinning ring, the combination with an inner and outer member, of a self-lubricating bearing member situated between said inner and outer members, an annular traveler situated between the bearing 40 member and the inner member and wear-resisting inserts extending through the bearing member and having their bearing faces flush with the inner face of the bearing 45 member and in position to be engaged by the traveler as it rotates.

3. In a spinning ring, the combination with inner and outer members, of a self-lubricating bearing member situated between 50 said inner and outer members and an annular traveler situated between the bearing member and the inner member, said traveler being provided with an upwardly-directed stem having a guide eye at its end 55 and a downwardly-depending wear-resist-

ing apron situated opposite said stem and adapted to engage the inner wall of the bearing member.

4. In a spinning ring, the combination with inner and outer members, of a self-lubricating bearing member situated between said inner and outer members and an annular traveler situated between the bearing member and the inner member, said traveler being provided with an upwardly-directed stem having a guide eye at its end 60 and a downwardly-depending wear-resisting apron situated opposite said stem and adapted to engage the inner wall of the bearing member, said apron having such proportions that it constitutes a counterbalance for the stem and guide. 65

5. In a spinning ring, the combination with an inner member presenting an annular horizontally-extending portion and an upwardly-directed flange at the inner edge of said horizontal portion, of an outer member presenting a circular vertical wall and an inwardly-extending flange at the upper end of said wall, an annular bearing member of relatively-soft self-lubricating material situated between the inwardly-directed flange of the outer member and the horizontal portion of the inner member and provided with an inwardly-directed flange 80 portion which extends over the upwardly-directed portion of the inner member, said horizontal portion of the inner member having pointed projections on its upper surface which are forced into the bottom face of the 85 bearing member when the outer, inner and bearing members are assembled whereby the bearing member will be firmly held against the flange of the outer member, and an annular traveler situated between the flange 90 of the bearing member and the upwardly-directed flange of the inner member. 95

6. In a spinning ring, the combination with an inner member and an outer member, of a self-lubricating bearing member confined between said inner and outer members, and an annular traveler situated between the bearing member and the inner member, said bearing member having separated portions of the surface thereof, against which 100 the traveler engages, harder than other portions. 105

In testimony whereof I have signed my name to this specification.

CHARLES S. FORBES.
